UNITED STATES PATENT OFFICE.

HUGO WEGELIN, OF AUGSBURG, GERMANY.

ELECTRICAL IGNITER FOR HYDROCARBON-ENGINES.

SPECIFICATION forming part of Letters Patent No. 654,693, dated July 31, 1900.

Application filed February 16, 1899. Serial No. 705,665. (No model.)

To all whom it may concern:

Be it known that I, HUGO WEGELIN, engineer, a subject of the Emperor of Germany, and a resident of Augsburg, in the Kingdom 5 of Bavaria, in the Empire of Germany, have invented certain new and useful Improvements in and Relating to Hydrocarbon-Engines, (for which I have made application for Letters Patent in Great Britain, No. 15,927, 10 bearing date July 21, 1898,) of which the following is a specification.

This invention relates to hydrocarbon-engines, and comprises means for effecting ignition of the motive fluid in which a continuous 15 current may be employed or in which an electromagnetic inductor is employed for the periodic generation of current to effect ignition as required.

The objects of the invention are to effect- 20 ively provide for the adjustment of the time of ignition and for the regulation of the amount of compression, according to the quality of the explosive charge, the load, and other conditions.

25 The invention consists in one part in the provision of an operating tappet or cam for effecting periodic making and breaking of the circuit of a continuous electric current with an oblique rear edge which may break 30 contact sooner or later, as may be required to effect early or late ignition, and in another part in the provision of an adjustable cam for operating the exhaust-valve operating-lever, such cam being provided with two pro- 35 jections to respectively operate the exhaust-valve, according to the amount of compression required or as the ignition is effected early or late.

The invention is illustrated in the accom- 40 panying drawings, in which—

Figures 1 and 2 are respectively part side elevation and plan of a motor applied with the improved means for effecting ignition. Fig. 3 is a part plan of a motor in which the 45 ignition-gear is slightly modified and an adjustable cam is provided for operating the exhaust-valve lever. Fig. 4 is a detail plan view of the adjusting means. Fig. 5 is a detail end view of said means, parts being in section.

50 In carrying the invention into effect a tappet or cam *e* is provided integral with or secured to a spur-wheel *d*, rotating upon a spin-

dle *d'*, mounted upon the engine-frame, such spur-wheel gearing with the pinion *b*, mounted upon the crank-shaft *c* of the motor *a* and having twice the number of teeth as the pinion *b*. The rear edge *f* of the tappet or cam *e* is oblique or inclined. The spring-contact *g* is provided to laterally slide within a groove *g'*, provided in the bracket *g*², secured to the engine-frame, so that upon the adjustment of the contact early or late ignition may be effected, the early ignition being effected on the adjustment of the spring-contact *g* into the position indicated in full lines in Fig. 2, 60 while late ignition is effected upon its adjustment into the position indicated in dotted lines in that figure.

Integral with or secured to the tappet or cam *e* and spur-wheel *d* is a cam *m*, provided for the purpose of operating the exhaust-valve lever *i* by contact with the roller *l*, provided at its extremity. When it is desired that the exhaust-valve should be opened on the compression-stroke, so as to reduce the amount 75 of compression—such, for instance, as when running at a reduced load or when starting—the parts are arranged as shown in Fig. 3. The tappet *e* and spur-wheel *d* are provided adjustable, so as to slide on the spindle *d'*, 80 the contact-spring *g* being accordingly fixed. The cam for operating the exhaust-valve lever is in this case provided with two projections *m'* and *n*, the former of which operates the exhaust-valve on the exhaust-stroke no matter what the position of the tappet *e*, while the latter is arranged to open the exhaust-valve only when the tappet is in position for late ignition, the cam being shown in this position in Fig. 3. By such means the motor may be 90 readily started without compression, while when running at a reduced load the compression may be wholly or partly prevented. When it is desired that the exhaust-valve shall not be opened on the compression-stroke—95 namely, when the tappet *e*, Fig. 3, is to be arranged for early ignition—the tappet *e* is moved along its spindle *d'* until the projection *n* clears the roller *l*, in which position, however, the projection *m* will contact with 100 the roller *l*, as usual, so as to open the exhaust-valve on the exhaust-stroke. The contact-arm *g* is held in any of its adjusted positions by means of a screw *g*³.

The electrodes are shown at x in Fig. 2, and these are of ordinary form, forming no part of my invention.

The battery is indicated at y , and the electrical connections at $z z'$, the circuit being completed through the frame and the shaft d .

The adjusting means for the tappet and cam n is shown in Figs 4 and 5, such means consisting of a bell-crank 3 , pivoted on a bracket 5 and operated by a rod 4 , the free end of the bell-crank being provided with rollers 6 , bearing one on each side of the wheel d , to which the cam n is secured. Operation of the rod 4 will cause the wheel, and therefore the cam n , to slide on its shaft d' .

Having now described my invention, what I claim as new, and desire to secure by Letters Patent, is—

1. In combination in an igniting device for gas-engines, a contact-piece, electric connections controlled thereby electrodes in said electrical connections and a tappet having an inclined edge adapted to effect early or late separation for early or late ignition according to the relative position of the contact and tappet, one of said parts being adjustable in relation to the other and means for operating the tappet as described.

2. In combination, in an igniting device, a rotary cam or tappet, an arm to engage the same, one of said parts being adjustable rela-

tive to the other, a shaft carrying the tappet, said tappet having its edge inclined with respect to the plane of the axis of rotation, electrical connections controlled by the arm and tappet and electrodes in said electrical connections substantially as described.

3. In combination in an igniting device for hydrocarbon-engines, a rotary tappet having an inclined edge, a device to engage the same, one of said parts being adjustable in relation to the other longitudinally of the inclined edge, electrical connections controlled by said tappet and said device and electrodes in said connections substantially as described.

4. In combination in an igniting device for gas-engines, a tappet having an inclined edge, the crank-shaft, a pinion mounted on the crank-shaft, a spur-wheel connected to the tappet, said spur-wheel rotating at one-half the speed of said pinion, a contact to engage the tappet electrical connections controlled by the tappet and contact, and electrodes in said electrical connections, substantially as described.

In witness whereof I have hereunto set my hand in presence of two witnesses.

HUGO WEGELIN.
